DESIGN.

E. W. TINGUE.

UPHOLSTERY PLUSH.

No. 18,890.

Patented Jan. 29, 1889.

UNITED STATES PATENT OFFICE.

EDWARD W. TINGUE, OF NEW YORK, N. Y., ASSIGNOR TO THE TINGUE MANUFACTURING COMPANY, OF SEYMOUR, CONNECTICUT.

DESIGN FOR UPHOLSTERY PLUSH.

SPECIFICATION forming part of Design No. 18,890, dated January 29, 1889.

Application filed December 28, 1888. Serial No. 294,871. Term of patent 3½ years.

To all whom it may concern:

- Be it known that I, EDWARD W. TINGUE, a citizen of the United States, residing at New York, county and State of New York, have invented a certain new and original Design for 5 Upholstery Plush, of which the following is a specification, reference being had to the accompanying photograph, which forms a part of the same.
- 10 This invention consists of a design for ornamenting the surface of fabrics of that class known as "upholstery plush."
- The accompanying photograph is a face view of my design.
- 15 This design consists of an endless scroll or vine pattern, and can be repeated any desired number of times upon the fabric. The photograph shows several repeats. A continuous stem or branch the general direction of which 20 is longitudinal and another stem or branch

the general direction of which is transverse or at right angles to the first form the continuous lines of the design through all the repeats. From these main stems curved branches, generally terminating in scrolls, project in various directions. The fabric (upholstery plush) to which this design is applied has a wrinkled surface, so that the peculiar appearance common to smooth plush is greatly heightened, and the effect of the design upon this surface 25 is both novel and beautiful.

Having now described my invention, what I claim, and desire to secure by Letters Patent, is—

The design for upholstery plush, consisting 30 of the design, substantially as shown.

EDWARD W. TINGUE.
